W. C. DILLON.
AUXILIARY LOCK FOR VAULT LOCK MECHANISM.
APPLICATION FILED FEB. 10, 1920.

1,404,937.

Patented Jan. 31, 1922.

UNITED STATES PATENT OFFICE.

WILLIAM C. DILLON, OF FORT DODGE, IOWA.

AUXILIARY LOCK FOR VAULT-LOCK MECHANISM.

1,404,937.

Specification of Letters Patent. Patented Jan. 31, 1922.

Application filed February 10, 1920. Serial No. 357,658.

To all whom it may concern:

Be it known that I, WILLIAM C. DILLON, a citizen of the United States, residing at Fort Dodge, in the county of Webster and 5 State of Iowa, have invented certain new and useful Improvements in Auxiliary Locks for Vault-Lock Mechanism, of which the following is a specification.

This invention relates to a device for preventing operation of the bolt lock mechanism of a safe or vault, and the primary object of the invention is to provide an improved means for operating said device, when the locking mechanism is being tampered with by unauthorized persons.

Another object of the invention is to provide an attachment for the ordinary bolt lock mechanism of a vault or safe which will be moved into operative position with 20 the bolt mechanism, when the combination lock has been forced inwardly by any means or burnt out by a gas or electric torch.

A further object of the invention is to provide a block rotatably carried by a vault 25 or safe door and adapted to be moved in the path of the vault bolt lock mechanism and held in position by a spring, and having means for holding the block out of the path of the bolt mechanism against the tension of said spring, said means being adapted 30 to be thrown out of operation when the combination lock mechanism is destroyed.

A still further object of the invention is to provide a novel means for carrying the 35 block and spring and for operatively connecting the same together.

Other objects and advantages of the invention will appear in the following detailed description taken in connection with the 40 drawings, forming a part of this specification, in which drawings:

Figure 1 is a fragmentary rear elevation of a vault door and frame showing the improved device applied thereto.

Figure 2 is a side elevation of the improved device.

Figure 3 is an end elevation of the improved device showing the same applied to a vault door the block being shown in full 50 lines in a raised position and in dotted lines in a lowered position in the path of the bolt locking mechanism.

Referring to the drawings in detail, wherein similar reference characters designate corresponding parts throughout the several

views, the letter A indicates the improved attachment for the bolt lock mechanism B of a vault or safe door C. The bolt mechanism B is adapted to engage the door frame D in the ordinary manner and held 60 in engagement therewith by the combination lock mechanism E. The bolt mechanism B, the door C, the frame D and the combination lock mechanism E are of the ordinary or any preferred construction, and the bolt lock 65 mechanism E includes the usual bolts 5 connected to the vertically extending bar 6 by suitable bolts 7 or other fastening elements. The bar 6 is provided with the inwardly extending arm 8, which is disposed in the path 70 of the combination lock mechanism E which prevents the sliding thereof when the combination has been set.

The door C includes the body 9 having the inwardly extending flange 10 which is 75 arranged adjacent to and parallel with the usual flange 11 carried by the door frame D. The combination lock mechanism E is secured to the reinforcing bar 12 which is carried by the body 9 of the door C in the ordinary or any preferred manner.

The improved auxiliary locking device A comprises a rod 13 which is adapted to be inserted through a suitable opening 14 formed in the flange 10. The opening in the 80 flange 10 may be drilled at any desired point so that the rod 13 can be placed at different points on different safes or vaults, and thereby render the finding of the same by a burglar practically impossible. While 85 the rod 13 may be positioned above the combination lock mechanism E, it has been shown for the purpose of illustration located below the same.

After the rod 13 has been placed in the 90 opening 14, the same is held against accidental displacement by a pair of lock nuts 15 which engage the opposite sides of the flange 10 and firmly hold the rod 13 in operative position. The outer faces of the lock nuts 15 may be, if so desired, milled or 95 serrated, so that a firm hold may be obtained thereon to permit adjustment thereof. The rod 13 extends inwardly from the flange 10 directly in rear of the connecting bar 6 100 of the bolts 5 and extends beyond said connecting bar. The portion of the rod 13 which extends beyond the bar 6 has threadably mounted thereon a substantially rectangular solid block 16. The threaded bore of 110

the block 16 is located adjacent to one end thereof, and when the block is turned on the rod 13 at right angles to the body 10 of the door C, the free end of the block lies in the 5 path of the connecting bar 6 for the bolts 5 and prevents operation of the bolts and thereby prevents the opening of the door. The free end of the rectangular solid block 16 is normally held in the path of the connecting bar 6 by means of a contractile helical spring 17 which has its upper terminal bent at right angles to provide an attaching arm 18 which is extended through a suitable 10 opening formed in the block 16 directly below the rod 13. The lower end of the spring 17 is bent to provide a hook or eye 19, which is adapted to be inserted through any one of a plurality of openings 20 formed in the flat attaching foot 21 carried by the lower 15 end of the vertical attaching bar 22. The rod 13 intermediate its ends is provided with a diametrically extending opening 23, which is threaded for the reception of the threaded end 24 of the attaching rod 22. The threaded end 24 of the attaching rod extends beyond the bolt and is held securely in place by a suitable nut and lock washer 25. The opening 23 for the reception of the attaching rod 22 may be located at any desired point 20 and may be provided in the terminal of the rod opposite to the terminal which is positioned in the opening 14 of the flange 10. In applying the device to a safe or vault door, the rod 13 is secured thereto in the 25 manner described above, and the block 16 is threaded to the desired place on the bolt directly in rear of the connecting bar 6, and the spring 17 is then placed in position.

The plurality of openings 20 are provided 40 so as to permit the spring 17 to be placed in any desired position according to the adjustment of the block 16. To normally hold the free end of the block 16 out of the path of the connecting bar 6, a cable 26 is extended 45 through the same opening as the spring 17, and extends upwardly therefrom across the face of the combination lock mechanism E and is anchored above the same to the reinforcing bar 12 as at 27. The cable 26 has a 50 turnbuckle construction 28 intermediate its ends so as to permit the adjustment or tensioning of the cable. In applying the cable 26 in position, the same is first anchored to its place above the combination lock 55 mechanism E and then secured to the upper end of the spring 17, and the block 16 is turned on the rod 13, and the turnbuckle mechanism 28 adjusted until the cable 26 has been shortened so as to hold the block 60 16 in its raised position against the tension of the spring.

When the combination mechanism has been forced inwardly by any method or burnt out by a gas or electric torch, the 65 cable 26 will be broken or burnt in two per-

mitting the spring 17 to draw the block 16 into the path of the connecting bar 6 and thus prevent the operation of the bolts 5.

The spring 17 is so tensioned that when the block 16 is positioned in the path of the 70 bar 6, the same will form a support for the block and hold the block against displacement.

When the cable 26 has been severed the same will drop down into the bottom of 75 the safe and vault and thereby prevent the burglar from reaching the same and pulling the block back to its normal position.

When the device is applied to a safe or vault door, the location of the same is made 80 known to the owner of the same by exact measurement, so that in case the safe has been tampered with by unauthorized persons the rod 13 can be at once located. After the block 16 has been operated and 85 thrown in the path of the connecting bar 6, a hole is drilled in the safe or vault door directly above the block 16 and a hook is inserted through the hole and placed in an opening or socket 29 formed in the free end 90 of the block for that purpose. The hook is then drawn forward, which will swing the block 16 on the rod 13 and permit the bolt mechanism B to be operated in the ordinary manner. 95

Changes in details may be made without departing from the spirit or scope of the invention; but,

I claim:

1. As a new article of manufacture, an 100 auxiliary locking device for the bolt mechanism of vault and safe doors comprising a threaded rod, means carried by the rod for connecting the same to a door, a block threaded on said rod, an attaching rod carried by and extending radially from the first rod, and a contractile coil spring connected to said attaching rod and block for normally tending to hold the block in one of its positions. 110

2. As a new article of manufacture, an auxiliary locking device for the bolt mechanism of vault and safe doors comprising a threaded rod, means carried by one end of the rod for connecting the same to a door, a 105 block threaded on the opposite end of the rod, an attaching rod carried by and extending radially from the rod and arranged intermediate the block and means for securing the rod to a door, a contractile coil 115 spring connected to said attaching rod and to the block, and a frangible cable connected to said block at the point of connection of the spring therewith. 120

3. The combination with a vault door of 125 a locking device therefor including a bolt mechanism, a combination mechanism, a rod carried by the door, a block adjustably carried by the rod and arranged to be moved into and out of the path of the bolt 130

mechanism, an attaching rod carried by the first mentioned rod, an angular extending foot formed on the attaching rod, a spring connected to the foot and block arranged 5 to normally urge the block into the path of the bolt mechanism, and an adjustable cable connected to the block and extended across the combination mechanism.

4. An attachment for the bolt mechanism 10 of a safe or vault door comprising a rod, a block rotatably mounted on the rod, an attaching rod secured to the first mentioned rod, an angular extending foot formed on the attaching rod, the foot having a plurality of spaced openings formed therein, a 15 contractile spring arranged to be secured in

any one of the openings and to the block, and a cable connected to said block.

5. An attachment for the bolt mechanism of a vault door comprising a threaded rod, 20 means for connecting the rod to a vault door, a substantially rectangular block adjustably and rotatably mounted on the threaded rod, an attaching rod secured to the first mentioned rod intermediate its ends, a flat attaching foot formed on the attaching rod, the foot having a plurality of openings formed therein, a contractile coil spring arranged to be secured in any one of the openings in the foot and to the block, and a 25 30 cable for the block.

WILLIAM C. DILLON.
